CLAIM

The ornamental design for a loudspeaker, substantially as shown and described.

DESCRIPTION

FIG. 1 is a perspective view of a loudspeaker as seen from the front, top, and side;

FIG. 2 is a front view thereof;

FIG. 3 is a back view thereof;

FIG. 4 is a top view thereof;

FIG. 5 is a bottom view thereof;

FIG. 6 is a side view thereof; and,

FIG. 7 is an opposite side view thereof.

The dotted line portions of the drawings represent environmental structure only and form no part of the claimed design. The broken line showing of numbers, words, and symbols forms no part of the claimed design.

1 Claim, 7 Drawing Sheets(56)
